UNITED STATES PATENT OFFICE

101,314

DESIGN FOR A SPORT SUIT

Arthur Steinman, Minneapolis, Minn.

Application July 10, 1936, Serial No. 63,754

Term of patent 7 years

To all whom it may concern:

Be it known that I, Arthur Steinman, a citizen of the United States, residing at Minneapolis, in the county of Hennepin and State of Minnesota, have invented a new, original, and ornamental Design for a Sport Suit, of which the following is a specification, reference being had to the accompanying drawing forming part thereof.

Fig. 1 is a front view of a sport suit, showing my new design. Fig. 2 is a rear view thereof.

Fig. 3 is an enlarged fragmentary view showing the right leg cuff member. Fig. 4 is a view similar to Fig. 3 showing the left leg cuff member.

I claim:

The ornamental design for a sport suit as shown.

In testimony whereof I hereunto affix my signature.

ARTHUR STEINMAN.
